MECHANISM FOR TRUING HOLES

Emil Mattson, Chester Depot, Vt., assignor to
 Bryant Chucking Grinder Company, Springfield, Vt., a corporation of Vermont

Application September 24, 1941, Serial No. 412,165

7 Claims. (Cl. 51—184.3)

This invention relates to mechanism for truing holes to render them accurately cylindrical and with their axes in predetermined relation to other parts. For example, such mechanism may be used to align spaced nearly aligned holes, or as in the case of engine cylinders, to line up cylinder bores in proper relation to the crankshaft.

One object of this invention is to provide a feeler or gage mechanism by manipulation of which the bore or hole may be tested for accurate cylindricity.

A further object is to provide improved means for adjusting the axis of the hole finishing mechanism by which this axis is brought into a predetermined relationship to other parts.

For a more complete understanding of this invention, reference may be had to the accompanying drawings in which

Figure 1 is a perspective view of a hone embodying certain of the features of this invention.

Figure 2 is a central longitudinal cross section of the hone of Figure 1 shown in work having a pair of spaced bores which are to be brought into axial alignment, this view showing axis adjusting mechanism.

Figure 3 is a fragmentary left hand elevation of the work shown in Figure 2 and showing the axis adjusting mechanism.

Figures 4 and 5 are detail sectional views, Figure 5 being to a larger scale, on section lines 4—4 and 5—5, respectively, of Figure 2.

Figure 6 is a detail section on line 6—6 of Figure 5.

Figure 7 is a fragmentary central section through an engine cylinder of a block showing the hone of Figure 4 applied thereto.

Figure 8 is a fragmentary diagrammatic longitudinal sectional view of an engine cylinder showing in full line an improperly positioned bore and in dotted line the corrected bore, the amount of correction being exaggerated for the sake of clarity.

Figure 9 is a detail section on line 9—9 of Figure 8 and showing the hone of Figure 1 within the cylinder bore and with the hone blades retracted and the gage feeler projected.

Referring first to Figures 1 to 4, at 1 is indicated a cylindrical body member having a plurality of radial slots therein within which ride cutting elements 2. While four such elements are illustrated, a greater or less number might be employed. These cutting elements may be of various forms, but as shown they are hones, each being provided with an external longitudinal sur-

face portion 3 carrying abrasive material, as, for example, by having abrasive material charged into its outer face. These elements 2 are arranged to be expandable or contractible, being contracted so as to permit the insertion of the body portion carrying them into a hole to be trued, and then expanded into contact with the inner face of the hole and further expanded as the hole increases in diameter due to the action of the cutting elements. This body with the cutting elements is arranged to be rotated and moved axially to perform its desired operation on the work and in order to support the body for such rotation and axial motion, it is shown as provided with tubular pilot members 5 and 6 at opposite ends thereof and arranged coaxial therewith.

Any suitable means may be provided for retaining the elements 2 in position and for expanding them to suit the diameter of the hole in which they are to be placed. As shown they are held in assembled relation to the body portion and urged into contracted position by spring rings 7 engaging in reduced end portions 8 thereof, and they may be projected outwardly as desired by the use of wedge or conical blocks 10 secured to an axially movable shaft 11 located in a central bore in the body 1. As shown these blocks are secured in recesses in the member 11 as by means of screws 12 and they act upon inclined wall portions 14 and 15 of recesses 16 and 17 in the elements 2. The member 11 may be adjusted axially with respect to the body member 1, and for this purpose the end thereof toward the larger end of the blocks 10 is engaged by a thrust bar 20 seated in a bore 21 of the pilot 6 and engaged at its outer end by a plug 22 seated in an enlarged diameter portion of the bore 21. This member 22 has threaded therein a stem 23 of a differential screw 24 which in turn is internally threaded into a socket portion 25 in the outer end of the pilot 6. The member 11 is pressed against the end of the thrust rod 21 as by means of a spring 26 engaging its opposite end, this spring reacting between the end of the element 11 and a closure plug 27 threaded into the outer end of a socket 28 in the end of the pilot 5.

For the purpose of this invention gage or feeler means are provided by which it can be determined by the operator when the hole within which the body 1 and its cutters 2 is positioned is accurately cylindrical and this without removing the tool from the work. Thus the gage member is accurately related to the cutting elements at all times

and the gaging is done from the same centering and with the same setting as the finishing of the hole. As shown the gage comprises a headed feeler element 30 slidable through a bushing 31 threaded into a hole 32 in the body 1 between two of the cutting elements 2. This feeler element is positioned with its shank portion 33 projecting outwardly and is normally held retracted as far as permitted, as by a coil spring 34 reacting between the head 35 of the feeler element and the base 36 of a socket in the bushing 31. The outer end of this shank 33 is rounded to form a surface which may be projected to the desired extent until it contacts with the inner wall 40 of the hole in the work and this projection of the feeler element may be accomplished by motion of a rod 41, one end of which is tapered as shown at 42 and engages between side shoulders 43 of the end face of the head 35. This rod 41 is provided with a head 45 at its opposite end and a spring 46 surrounding this element reacts between the base of the head 45 and the base 47 of an enlarged diameter portion of a bore 48 within which the rod 41 is axially movable. This spring tends to hold the rod 41 retracted so that the feeler element 33 is retracted and so held by the spring 34. A plug 50 threaded into the outer enlarged end portion of the bore 48 and also through a hole 51 in an inner flanged extremity 52 of the pilot member 6 engages the head 45, and by manipulation of this plug 50 the feeler element can be projected or retracted. This plug 50 is located and accessible for adjustment from within the periphery of the body member.

When the tool is being used to align a pair of spaced holes in work, as, for example, the holes 40 and 60 shown in Figure 2, a bushing 61 within which the pilot portion 6 of the tool may be journaled and of a proper size to closely fit one of these holes as 60 is inserted in that hole. The hole 60 is then taken as the basis for the correct axial position, and the hole 40 is trued into accurate alignment therewith. The pilot 5 is then supported for rotation and axial motion in a bushing 55 and this bushing is arranged to be adjusted laterally of the work as may be necessary to true the hole 40 into proper axial alignment with the hole 60. As shown this bushing 55 is adjustably mounted as by screws 56 positioned in angular spaced arrangement therearound, these screws being threaded through an annular member 57 forming part of a locating plate 58. This locating plate is firmly fixed to the work as by means of bolts 59, which pass therethrough and through spacer sleeves 62 and are threaded into the work. The locating plate is thus firmly secured to the work and by adjustment of the screws 56 the pilot portion 5 may be brought into the correct position, taking up any spring in the pilot portions 5 and 6 so that as the truing of the hole 40 progresses, it is brought into accurate coaxial relation with the bore 60.

After a desired amount of rotation and axial motion of the tool with the cutting elements outwardly adjusted as desired, the correctness of the truing may be tested from time to time as by the feeler element. When this is desired, the cutting elements are retracted by proper turning of the plug 24 and the feeler element is adjusted outwardly into contact with the work. If the work is not truly cylindrical, rotation of the work with the gaging element in contact with its inner face cannot be done throughout its entire circumference but when the truing has been completed, the gaging element when moved into contact with

the inner face of the work will permit the tool to be rotated throughout a complete circumference at any point lengthwise of the bore where the feeler element may contact with the interior of the hole, and when this has been determined by testing the truing operation that particular hole is complete.

This device may be employed also for truing cylinders for engines into accurate perpendicular relation to the crank shaft. Mechanism for so using the tool is illustrated somewhat diagrammatically in Figures 7 and 8. Referring to these figures, at 100 is indicated the cylinder block for the engine with a crank case portion 101. This is placed in a fixture having lower and upper parts 102 and 103, the fixture having suitable means (not shown) for correctly locating the crank shaft center 104 and its upper portion correctly locating a bushing 105 having a hole 106 for one of the pilot portions 5 or 6 and its lower portion having a pilot guide 108 so that when the hole is coaxial with this bushing and pilot guide it will be exactly perpendicular to the crank shaft axis 104. The bushing 105 is preferably of a diameter larger than that of the cylinder bore so as to permit the tool to be removed endwise from the cylinder bore through the hole which receives the bushing 105, thus to permit ready application and removal of the tool for inspection of the bore or other purpose.

In Figure 8 is illustrated an inaccuracy in the original cylinder bore indicated in full lines, while in dot and dash lines is shown the final diameter and position of the bore correctly related to the crank shaft. This inaccuracy is shown much exaggerated, this being for the purpose of more clearly illustrating it.

With the honing tool in position as shown in Figure 7, the finishing of the interior of the cylinder bore is effected, the cutting elements being expanded from time to time as the hole is enlarged until such time as when tested by the feeler element the hole is truly cylindrical. At this time it will have been not only formed truly cylindrical, but in accurate perpendicular relation to the crank shaft axis so that when the engine is assembled the cylinder will be lined up properly with relation to the crank shaft.

From the foregoing description of an embodiment of this invention and certain uses to which it may be applied, it should be evident to those skilled in the art that various changes and modifications might be made without departing from its spirit or scope.

I claim:

1. A device of the class described, comprising a body member, a plurality of cutting elements carried by said body member spaced angularly about its axis, means for simultaneously moving said elements from and toward the axis of said body member, a feeler element fixed during operation of the device and carried by said body member between certain of said cutting elements, and means for adjusting said feeler element toward and from the axis of said body member.

2. A device of the class described, comprising a body member, a plurality of cutting elements carried by said body member spaced angularly about its axis, means for simultaneously moving said elements from and toward the axis of said body member, a feeler element fixed during operation of the device and carried by said body member between certain of said cutting elements, an element movably carried by said body member and accessible for movement at one end of

said body member, and operative connections from said movable element to said feeler element for causing movement of said movable element to adjust said feeler element laterally with reference to the axis of said body member.

3. A device of the class described, comprising a body member, a plurality of cutting elements carried by said body member spaced angularly about its axis, means for simultaneously moving said elements from and toward the axis of said body member, a feeler element fixed during operation of the device and carried by said body member between certain of said cutting elements, an element movably carried by said body member and accessible for movement at one end of said body member and within the periphery thereof, and operative connections from said movable element to said feeler element for causing movement of said movable element to adjust said feeler element laterally with reference to the axis of said body member.

4. A device of the class described, comprising a cylindrical body member, a plurality of cutting elements carried by said body member spaced angularly about its axis, means for simultaneously moving said cutting elements from and toward said axis, said body member having a longitudinally extending bore at one side of said axis between a pair of said elements and a hole through the periphery of said body member intersecting said bore, a sleeve seated in said hole, a headed feeler element projecting through said sleeve and with its head inwardly disposed, a spring positioned between said head and sleeve for retracting said element, a wedge element axially movable in said bore and having a wedge face in engagement with said head to force said feeler element outwardly against the action of said spring as the thicker part of said wedge portion engages said head through axial motion of said wedge element, a spring forcing said wedge element in the reverse direction, and a member

threaded through an end portion of said body member and engaging said wedge element for controlling the axial position of said wedge element, said threaded member being accessible for turning at said body member end.

5. In combination with a cylindrical body portion, cutting elements arranged about the axis of said body portion, pilot members extending coaxially from opposite ends of said body portion, bushings within which said pilot members are journaled, a frame, means for securing said frame to the work around one end of the hole to be treated, and means for adjusting one of said bushings relative to said frame transverse to the axis of said hole.

10 6. In combination with a cylindrical body portion, cutting elements arranged about the axis of said body portion, pilot members extending coaxially from opposite ends of said body portion, bushings within which said pilot members are journaled, a frame having an opening therethrough larger than one of said bushings, means for securing said frame to the work adjacent to one end of the hole to be treated, and screws 20 carried by said frame for engaging said one bushing and adjusting said one bushing laterally of the axis of said body member within said frame opening.

7. In combination with a cylindrical body portion, cutting elements arranged about the axis of said body portion, pilot members extending coaxially from opposite ends of said body portion, bushings within which said pilot members are journaled, a fixture having coaxial spaced holes 30 for receiving said bushings and between which work to be acted on by said cutting elements may be positioned, one of said bushings being of a diameter larger than that of said body portion to thereby permit the withdrawal of said body portion from the work through the hole which 35 normally receives and holds said one bushing.

40 EMIL MATTSON.
